B. F. Goodrich Company, New York, N. Y., a
corporation of New York

Application January 20, 1943, Serial No. 472,972

16 Claims. (Cl. 244—134)

This invention relates to separable connectors and especially to plug and receptacle assemblies for mounting between a pair of adjacent structures and for conducting fluid.

Objects of the invention are to provide for effectively joining a pair of structures in an improved quick-detachable manner, to provide for externally interconnecting the structures while providing for the flow of fluid, to provide for fluid-tightness of the connection while permitting angular misalignment and movement, to provide for the smooth flow of fluid under pressure and for resisting accidental disengagement of the separable connector assembly, and to provide for convenience of manufacture, simplicity of construction, and convenience and reliability of operation and assembly.

More specific objects of my invention are to provide means for facilitating the installation of an inflatable protective covering for preventing the accumulation of ice upon an airfoil, to provide for externally connecting the covering in a separable self-sealing manner to a source of fluid within the airfoil while withstanding pressure, suction, and low temperature conditions, to provide for preventing air flow from within the airfoil to space between the airfoil and the protective covering, and to provide for permitting flow of fluid while the protective covering is in a collapsed condition.

These and other objects and advantages of the invention will be apparent from the following description.

In the accompanying drawings, which form a part of this specification, and in which like numerals are employed to designate like parts throughout the same,

Fig. 1 is a view in elevation showing a separable fluid-conducting connector assembly secured to an airfoil and to an inflatable protective covering, and constructed in accordance with and embodying the invention, parts being broken away and in section and being in a disengaged condition.

Fig. 2 is a view like Fig. 1 but showing the connector assembly in an engaged condition.

Fig. 3 is a view showing a plug and a receptacle for the connector assembly of Fig. 1, parts being broken away and in section.

Fig. 4 is a view in elevation showing a modified construction of the connector assembly, parts being broken away and in section.

Fig. 5 is a view in elevation showing a further modification of the connector assembly, parts being broken away and in section, and

Fig. 6 is a view looking to the right of the struc-

ture of Fig. 5, parts being broken away and in section.

In the illustrative embodiment of the invention shown in Figs. 1 to 3 of the drawings, a plug 10 and a receptacle or socket 11 for a separable fluid-conducting connector assembly 12 are attached to the margins of respective apertures 13 and 14 in an inflatable protective covering 15 and an airfoil 16, such, for example, as an airplane wing. The inflatable covering may be used for preventing the accumulation of ice in a manner, for example, as is disclosed in Geer Patent No. 1,998,809. The plug 10 and the receptacle 11 are made, preferably, of a resilient rubber or other rubber-like material, molded and vulcanized; although other suitable plastic, or even non-plastic materials such as metal may in some cases be used.

The plug 10 comprises an annular body having a flanged end 17 and a bore 18 of substantially uniform diameter for conducting a fluid, such as air, through the annular body into an inflatable tube 19 in the protective covering 15. The flanged end 17 is tapered in section and may have a suitable reinforcement 20, such as a woven fabric, as shown especially in Fig. 3, for maintaining the circular shape of the flanged end 17 despite the tendency of the margin of the aperture 13 in the protective covering 15 to distort under tension induced by inflation of the tube 19.

It is desirable to secure the plug 10 at the flanged end 17 to the protective covering 15, in the manner shown in Figs. 1 and 2, by a suitable adhesive such as rubber cement; however, the flanged end may instead be adhered to the exterior surface of the covering 15 adjacent the airfoil 16. In the arrangement shown in Fig. 1, a ribbed bleeder element 21 is disposed, preferably, in the inflatable tube 19 over the bore 18 at the flanged end 17 for assuring flow of fluid when the protective covering 15 is in a deflated condition.

By virtue of the shape of the flanged end 17, which permits its conformance to the surface of the airplane wing 16 and permits a snug fit with the receptacle 11, the protective covering 15 may be installed upon the airplane wing 16 at the leading edge, as shown in Fig. 2, in a tightly stretched condition and free of objectionable air pockets between the covering 15 and the wing 16 surface and free of objectionable protuberances which cause a loss of aerodynamic efficiency of the wing.

The annular body of the plug 10 has a substantially hemispherical or generally bulbous end portion 22 opposite the flanged end 17 and an in-

termediate reduced portion 23 tapering from the substantially hemispherical end to the flanged end. The annular body is proportioned such that it will not buckle under axial compression which may be caused by frictional engagement with the receptacle 11.

The intermediate reduced portion 23 permits angular misalignment with the receptacle 11; while the substantially hemispherical end portion 22 permits sealing contact with the receptacle for all conditions of misalignment, the thicker wall at the end portion 22 resisting undue compression and insuring a tight seal in the region of the bulbous end 22 during engagement of the plug 10 and the receptacle 11.

For completing the connection of the inflatable protective covering 15 in a separable manner to the source of fluid, the receptacle 11 is mounted in an aperture 14 in the airfoil 16 or airplane wing, as shown in Figs. 1 and 2. Preferably, a metal reinforcing plate 24, which may be of aluminum alloy, is attached, as by riveting, to the margin of the aperture 14 in a wing skin 16a of aluminum alloy, for example, and the plate 24 has an aperture 25 with a countersunk margin 26 for retaining the receptacle 11 in position for engaging the plug 10 and for providing space for the flanged end 17 of the plug.

The receptacle or socket 11 of resilient rubber-like material has a generally frusto-conical body 27 and a hollow cylindrical end portion 28 for connecting to a fluid conduit 29, such, for example, as metal or other tubing of suitably stiff material, which is interconnected with a source of supply of fluid, such as air under pressure. The body 27 has, preferably, a substantially concentric frusto-conical bore 30 terminating in a bore 30a of substantially uniform diameter at the cylindrical end portion 28, the latter bore 30a being substantially the same diameter as that of the bore 18 of the plug 10 and as the internal diameter of the fluid conduit 29 for providing for smooth flow of fluid through the separable connector assembly 12. However, the bore 30 may be of substantially uniform diameter and of a diameter suitable for providing for elastically gripping the bulbous end 22 of the plug 10. The fluid conduit 29 registers against a shoulder portion 31 at the region of the bore 30a and is retained in position by a clamping ring 34 and desirably by a suitable adhesive like rubber cement.

As shown in Fig. 3, the body 27 has a sealing lip 32 at the end opposite the cylindrical end portion 28 for contacting the countersunk margin 26 of the aperture 25 in the plate 24, the sealing lip being substantially normal to the axis of the body 27 as molded and being flexed, as shown by dotted lines, when the receptacle 11 is mounted on the plate 24 to exert sealing pressure against the margin 26. The sealing lip 32 may, if desired, be adhered to the margin 26 by a suitable adhesive like rubber cement. A recess 33 adjacent the lip 32 provides for seating the margin 26, which together with the sealing contact of the lip 32 with the margin 26 due to flexure of the lip 32 prevents air leakage from within the airplane wing 16 to the space between the protective covering 15 and the wing skin 16a thereby effectively preventing objectionable bulging of the protective covering.

The wall of the generally frusto-conical body 27, as shown in Figs. 1 and 3, is of an internal diameter and a thickness such as to provide for elastically gripping and sealing with the generally bulbous end 22 of the plug 10 under the condi-

tions of angular misalignment and internal fluid pressure. Also, when under a condition of suction, the body 27 tends to diminish in diameter by virtue of the elasticity of the rubber-like material, thus increasing the effectiveness of the elastic gripping and sealing action of the wall upon the plug 10.

In the operation of the separable connector assembly 12 for conducting fluid to the inflatable protective covering 15 for preventing the accumulation of ice upon the airplane wing 16, the plug 10 including the ribbed bleeder element 21 is attached to the protective covering as described hereinabove and the receptacle 11 is inserted in the aperture 14 in the wing 16. The receptacle 11 is mounted upon the margin 26 of the aperture 25 in the plate 24 by seating the margin 26 in the recess 33 and by flexing and desirably adhering the sealing lip 32 into contact with the margin 26, whereby a depression 35 is provided, as shown especially in Fig. 2, for receiving the flanged end 17 of the plug 10 and for movement and angular misalignment of the plug with respect to the bore 30 of the receptacle 11. Then the fluid conduit 29 is connected to the cylindrical end portion 28 of the receptacle in a fluid-tight manner, using the clamping ring 34 for this purpose. However, the fluid conduit 29 may be secured to the receptacle 11 before the receptacle is mounted in place as described hereinabove.

Furthermore, the leakage of air from within the wing 16 to the space between the protective covering 15 and the wing skin 16a through the aperture 25 is prevented effectively by the sealing lip 32 and the recess 33 being in contact with the margin 26. Thus, the aerodynamic efficiency of the wing 16 is not reduced by objectionable outward bulging of the protective covering 15 due to flow of air from within the wing under flight conditions.

To engage the plug 10 with the receptacle 11, the plug is inserted in the bore 30 to the position shown in Fig. 2, the resilient wall of the generally frusto-conical body 27 elastically gripping and sealing with the substantially hemispherical end 22 of the plug despite movement and angular misalignment which may occur during the alternate inflation and deflation or during the installation of the protective covering 15 upon the airplane wing 16. For greater ease of insertion of the plug, the bore 30 of the receptacle 11 may be lubricated with deflocculated graphite, glycerine, wax, or other suitable lubricants, which are not harmful to the rubber-like material of the plug and receptacle.

The bore 18 of the plug 10 is in register with the bore 30a and the opening in the fluid conduit 29 during engagement of the plug and receptacle for facilitating smooth flow of fluid through the connector assembly 12. The flanged end 17 of the plug fits into the depression 35 adjacent the sealing lip 32 of the receptacle, which permits movement of the plug and permits the protective covering 15 to conform to the wing skin 16a without objectionable protuberance. Also, any tendency of the plug 10 to slide out of engagement with the receptacle 11, when fluid under pressure is admitted to the connector assembly 12 or during the operation of the protective covering, is resisted by the pressure of the fluid within the tube 19 acting upon the area of the flanged end 17 of the plug. There is substantially no reduction of the elastic gripping action upon the plug 10 under varied temperature conditions of opera-

tion encountered, for example, during flight; inasmuch as the thermal coefficient of expansion and contraction of the rubber-like material of the plug and of the receptacle is substantially identical.

In the modified construction shown in Fig. 4, the separable fluid-conducting connector assembly comprising a plug 40 and a receptacle on socket 41, is arranged in an operative manner with the inflatable protective covering 15 and the airfoil 16 or airplane wing. The plug 40 has an annular body 42, preferably of resilient rubber or other rubber-like material and has a cylindrical element 43 of stiff material, such as metal or a suitable plastic material, and includes a bore 44 of substantially uniform diameter extending therethrough. It is desirable to unite the body 42 and the element 43 as by molding and vulcanizing in which case the element 43 is provided with a flange 45 for embedding in the body 42 of rubber-like material.

The annular body 42 has a flanged end 46 tapered in section for attaching at the margin 47 of an aperture 48 in the covering 15, the flanged end 46 having a plurality of spaced-apart grooves 49 in a face thereof adjacent the wall 15a of the covering 15 opposite the wall 15b having the aperture 48, the grooves extending outwardly, preferably radially, from the bore 44 for assuring flow of fluid while the covering 15 is in a deflated condition. The flanged end 46 is secured to the inner surface of the wall 15b of the inflatable covering 15 as by a suitable adhesive such as rubber cement, and conforms, by virtue of its shape, to the surface of the airplane wing 16 without objectionable bulging of the covering 15. The cylindrical element 43 of the plug 40 engages with the receptacle 41 in a separable manner.

The receptacle 41 of resilient rubber-like material has, desirably, a generally frusto-conical body 50 and a hollow cylindrical end portion 51 for connecting to a fluid conduit 29 in a manner as described hereinabove for Fig. 1 assembly. The body 50 has a sealing lip 52 for contacting the countersunk margin 26 of the aperture 25, the sealing lip 52 like the lip 32 being substantially normal to the axis of the body 50 as molded and being flexed, when the receptacle 41 is mounted in place in the aperture 25 in the airplane wing 16, to exert sealing pressure against the margin 26. The sealing lip 52 may be adhered in place, if desired, by a suitable adhesive such as rubber cement. A recess 53 adjacent the lip 52 provides for seating the margin 26, to co-act with the sealing lip 52 in preventing leakage of air from within the airplane wing 16 in the manner described hereinabove for the assembly shown in Fig. 1.

The body 50 has a bore 54 including an inwardly extending portion 54a extending from the flanged end 52 and terminating in a bore 54b of substantially uniform diameter at the hollow cylindrical end portion 51, the latter bore 54b being substantially the same diameter as that of the bore 44 of the plug 40 and as the internal diameter of the fluid conduit 29 for obtaining smooth flow of fluid through the separable connector assembly. The bore 54 at the inwardly extending portion 54a is of a diameter less than the diameter of the cylindrical element 43 and the wall of the body 50 is of suitable thickness to provide for elastically gripping and sealing with the cylindrical element 43 of the plug 40 at the portion 54a.

With the arrangement shown in Fig. 4, angular 75

misalignment and movement of the plug 40 is permitted while smooth flow of fluid is facilitated through the connector assembly. The flanged end 46 of the plug 40 is disposed in the depression 55 and conforms to the curvature of the airplane wing 16 without undue bulging of the protective covering 15. Also, any tendency of the plug 40 to slide out of engagement with the receptacle 41 during the operation of the inflatable covering 15 is resisted by the pressure of the fluid within the tube 19 acting upon the area of the flanged end 46 to maintain the plug 40 in its engaged position.

The arrangement shown in Figs. 5 and 6 is like that shown in Fig. 1 in many aspects but is especially useful for facilitating the installation of a protective covering 60 having one or more pairs of adjacent inflatable tubes 61 and 62 which are inflated, desirably, substantially simultaneously. 15 The separable, fluid-conducting connector assembly comprises a plug 63 of resilient rubber or other rubber-like material and a receptacle or socket 64 having a body 65 of rubber or other rubber-like material and, preferably, a hollow 20 cylindrical end portion 66 of stiff material, such, for example, as plastic or metal tubing.

The plug 63 comprises an annular body having a pair of spaced-apart flanges 67 and 68 at one end and a bore 69 of substantially uniform diameter extending partly therethrough from the opposite end. The flange 68 is generally rounded and tapered in section while the flange 67 is tapered in section, the flanges 67 and 68 being preferably annular in shape and being joined by 35 a pair of spaced-apart, substantially diametrically disposed partitioning ribs 70 for providing for side apertures 71 and 72 between the flanges for communication between the bore 69 or fluid conduit and the inflatable tubes 61 and 62.

40 The respective portions of the flanges 67 and 68 at each side of the partitioning ribs 70 are secured to the exterior surfaces of the margins 73a and 73b and 74a and 74b of apertures 75 and 76 in the tubes 61 and 62 by a suitable adhesive such as rubber cement; and ribbed bleeder elements 77 and 78 are similarly secured, desirably, in the tubes 61 and 62 at the region between the flanges 67 and 68 for assuring flow of fluid while the tubes 61 and 62 are in a collapsed condition. The ribs of the bleeder elements 77 and 78 are disposed, preferably, in a radially, outwardly extending manner, but may be disposed in any other suitable manner whereby flow of fluid is permitted despite a collapsed condition of the tubes 61 and 62.

45 The annular body of the plug 63 has a substantially hemispherical or generally bulbous end portion 79 opposite the flanges 67 and 68 and an intermediate reduced portion 80 tapering from the substantially hemispherical end to the flanges. The annular body is proportioned such that it will not buckle under axial compression which may be caused by frictional engagement with the receptacle 64.

50 The body 65 of the receptacle 64 is generally frusto-conical in shape and has a sealing lip 81 for contacting the margin 26 of the aperture 25 in the plate 24, the sealing lip being, if desired, adhered to the plate 24 as by a rubber cement, and has a recess 82 adjacent the lip 81 for seating the margin 26. In the manner as described above for Fig. 1, leakage of air from within the airplane wing 16 to the space between the protective covering 60 and the wing skin 16a is prevented effectively whereby the aerodynamic

efficiency is maintained by the elimination of undue bulging of the protective covering 60.

The body 65 has a bore 83 of substantially uniform diameter extending from the sealing lip 81 and terminating in a bore 84 of substantially uniform lesser diameter for registering with the bore 69 of the plug 63. The bore 83 is of a lesser diameter than the diameter of the generally bulbous end 79 for providing for elastically gripping the plug 63 in engagement with the receptacle 64. The metal tubing 66 has an internal diameter substantially equivalent to the bore 84 and has, preferably, a flanged end 66a for molding and vulcanizing the metal tubing 66 integral with the body 65 at the region of the bore 84. A fluid conduit 85, such as flexible hose, is attached to the metal tubing 66 by a suitable clamping ring 86 and may be adhered in place, if desired, by a suitable adhesive such as rubber cement.

The plug 63 and receptacle 64 are engaged in the manner described hereinabove for Figs. 1 to 3, the resilient wall of the body 65 elastically gripping the generally bulbous end 79 while permitting axial misalignment and movement of the plug 63. The wall of the bore 83 may be lubricated by a suitable lubricant such as glycerine for ease of inserting the plug 63. Upon engagement of the plug 63 with the receptacle 64, the flange 67 is disposed adjacent the sealing lip 81 in the space 87 for providing for a smoothly curved exterior surface of the protective covering 60 for promoting smooth flow of air over the wing 16. Thus the aerodynamic efficiency of the airfoil is substantially maintained.

Variations may be made without departing from the scope of the invention as it is defined in the following claims.

I claim:

1. A plug for conducting fluid and for separably engaging a socket, said plug comprising a body having a fluid conduit therein and including an outwardly bulged, elastic portion of greater wall thickness than adjacent portions of said body for elastically engaging in said socket in sealing relation therewith.

2. A plug for conducting fluid and for separably engaging a socket, said plug comprising a body having a fluid conduit of substantially uniform bore extending therethrough and including a flexible attaching flange at one end and an elastic portion of generally bulbous shape of greater wall thickness than adjacent portions of said body at the opposite end for elastically engaging in said socket in sealing relation therewith and having a reduced portion intermediate said elastic portion and said flange.

3. A plug for separably engaging in a socket and conducting fluid therethrough into an inflatable container, said plug comprising a body of resilient rubber-like material including a fluid conduit therein and including a pair of spaced-apart flanges at an end thereof for attaching at a margin in the inflatable container with a portion of said container between said flanges.

4. A plug for separably engaging a socket, said plug comprising a body of resilient rubber-like material having a substantially uniform bore therein extending from an end thereof and including a resiliently deformable portion of generally bulbous shape of greater wall thickness than adjacent portions of said body for separably engaging in said socket.

5. A socket for holding a plug and adapted for mounting in an aperture in a wall, said socket comprising a body having at one end a flexible

flange of resilient rubber-like material for contacting the margin of said aperture, and said body having a bore extending from said flexible flange for receiving said plug in sealing relation therewith, said bore being at least as large at the flanged end as at positions inwardly thereof to accommodate entry of said plug and the wall of said bore being resilient for elastically gripping said plug.

6. A socket for holding a plug and adapted for mounting in an aperture in a wall, said socket comprising a body having at one end a sealing lip for contacting the margin of said aperture and a recess adjacent said lip for seating said margin, and said body having a bore extending from said lip for admitting said plug and having an elastic portion intermediate the ends of said body for elastically gripping the plug, said bore being of gradually decreasing size at positions inwardly of the lip end to accommodate entry of said plug.

7. A socket for a fluid-conducting plug and adapted for mounting in an aperture in a wall, said socket comprising an annular body of elastic material including a sealing lip at one end for contacting the margin of said aperture, said annular body having a bore extending from said sealing lip and terminating in an opening of substantially uniform diameter for registering with a fluid-conduit in said plug, the wall of said bore being elastic for gripping the plug in sealing relation therewith, said bore being at least as large at the lip end as at positions inwardly thereof to accommodate entry of said plug.

8. A socket for a fluid-conducting plug and adapted for mounting in an aperture in a wall, said socket comprising a generally frusto-conical body of resilient rubber-like material and including a cylindrical end portion for connecting to a fluid conduit, said body having a sealing lip at the end opposite said cylindrical portion for contacting the margin of said aperture and having a bore extending from said lip and terminating at said cylindrical end portion in an opening of substantially uniform diameter for registering with a fluid conduit in said plug, said bore being of gradually decreasing size at positions inwardly of the lip end to accommodate entry of said plug and the wall of said bore being resilient for elastically gripping said plug.

9. An inflatable container and plug assembly for separably engaging a socket for conducting fluid to said container, said assembly comprising an inflatable container and a plug, said plug comprising a body of resilient rubber-like material including a fluid conduit of substantially uniform bore extending therethrough and a flanged end for attaching at the margin of an aperture in said container, said body having a resilient end portion of generally bulbous shape of greater wall thickness than adjacent portions of said body opposite the flanged end and being of a size greater than at least a part of the inner diameter of said socket for elastically and separably engaging said socket in sealing relation therewith and said body having a reduced portion intermediate the bulbous end portion and said flanged end, and means at said flanged end for assuring flow of fluid while said inflatable container is in a collapsed condition.

10. An inflatable container and plug assembly for separably engaging a socket for conducting fluid to said container, said assembly comprising an inflatable container and a plug, said plug comprising a body of resilient rubber-like ma-

terial including a fluid conduit extending therethrough and having a flanged end for attaching at the margin of an aperture in said container and at the inner surface of the wall of said container, said flanged end having a plurality of spaced-apart grooves extending outwardly in a generally radial manner from said fluid conduit in a face opposite said aperture and within said container for assuring flow of fluid while said container is in a collapsed condition, and a tubular element of stiff material secured to said body for separably engaging said socket, said element having a substantially uniform bore in communication with said fluid conduit of said body and having an end portion embedded in said body.

11. A separable, fluid-conducting connector assembly for mounting between a pair of adjacent structures, said assembly comprising a plug having a body including a fluid conduit of substantially uniform bore therein and a resilient portion of greater wall thickness than adjacent portions of said body, and said body including a flexible flange at an end thereof for attaching at a margin in one of said structures, and a socket having a body including a flexible flange at one end for contacting the margin of an aperture in the other said structure, said body of said socket having a bore extending therethrough from said end for receiving said plug in separable and sealing relation, said bore of said socket being at least as large at the flanged end as at positions inwardly thereof to accommodate entry of said plug and the wall of the latter said bore being resilient for elastically gripping said resilient portion of said plug.

12. A separable, fluid-conducting connector assembly for mounting between a pair of adjacent structures, said assembly comprising a plug having a body of resilient rubber-like material including a fluid conduit therein and including a pair of spaced-apart flanges at an end thereof for attaching at a margin in one of said structures with a portion of said margin between said flanges, said body having a side aperture between said flanges for communication between said fluid conduit and said structure, and a socket having a body including a flexible flange at one end for contacting the margin of an aperture in the other said structure, said body of said socket having a bore extending therethrough from said end for receiving said plug in separable and sealing relation, said bore being at least as large at the flanged end as at positions inwardly thereof to accommodate entry of said plug and the wall of said bore being resilient for elastically gripping said plug.

13. A separable, fluid-conducting connector assembly for mounting between a pair of adjacent structures, said assembly comprising a plug having a resilient body of rubber-like material including a fluid conduit of substantially uniform bore therein and a flanged end for attaching at the margin of an aperture in one of said structures and said plug having an end portion of generally bulbous shape opposite said flanged end, said end portion being of greater wall thickness than adjacent portions of said body, and a socket having a resilient body of rubber-like material including a flange at one end for contacting the margin of an aperture in the other said structure and including a bore extending therethrough from said end for receiving said plug in separable and sealing relation, said bore being of gradually decreasing size at positions inwardly of the

flanged end of said socket to accommodate entry of said plug and the wall of said bore being resilient for elastically gripping said plug.

14. In a separable connector assembly for conducting fluid from within an airfoil to an inflatable protective covering on the airfoil, in combination, an elastic plug having a bore of substantially uniform diameter and including a flanged end for attaching at the margin of an aperture in said covering, said plug having a generally bulbous end portion opposite the flanged end and an intermediate reduced portion; an elastic receptacle for receiving said plug and including a sealing lip at one end for contacting the margin of an aperture in said airfoil and a recess adjacent said sealing lip for seating the latter said margin, said receptacle having a countersunk bore extending from the sealing lip and terminating at the opposite end of the receptacle in an opening of substantially uniform diameter for registering with the bore of said plug, the bore of said receptacle being of a diameter less than the plug for elastically gripping the generally bulbous end of said plug; and means for assuring the flow of fluid from said plug while the protective covering is in a deflated condition.

15. In a separable connector assembly for conducting fluid from within an airfoil to an inflatable protective covering on the airfoil, in combination, a plug of resilient rubber-like material having a bore of substantially uniform diameter therein and including a pair of spaced-apart flanges at an end thereof for attaching at the margin of an aperture in said covering and said plug having a side aperture between said flanges for communication between said bore and said covering and including a substantially hemispherical end portion opposite the flanged end and an intermediate reduced portion tapering from said substantially hemispherical end portion to the flanged end; a receptacle of resilient rubber-like material for receiving said plug, said receptacle comprising a generally frusto-conical body and a substantially cylindrical end portion for connecting to a fluid conduit, said frusto-conical body having a countersunk bore in communication with and terminating at said substantially cylindrical end portion in an opening of substantially uniform diameter for registering with the bore of said plug, the wall of said frusto-conical body being of a diameter less than said plug for elastically gripping the plug at said substantially hemispherical end portion, and said frusto-conical body having a sealing lip opposite said substantially cylindrical end portion for contacting the margin of an aperture in said airfoil and having a recess adjacent said lip for seating the latter said margin; and a ribbed bleeder element disposed between said flanges of said plug for permitting flow of fluid while said protective covering is in a collapsed condition.

16. In a separable connector assembly for conducting fluid from within an airfoil to an inflatable protective covering on the airfoil, in combination, a plug including an annular body of resilient rubber-like material and a tubular element of stiff material and having a bore of substantially uniform diameter extending through said annular body and said tubular element, said annular body including a flanged end opposite said tubular element for attaching at the margin of an aperture in said covering and at the inner surface of the wall of said covering, said flanged end having a plurality of spaced-apart

grooves in a face opposite said aperture and within said covering for assuring flow of fluid while said covering is in a collapsed condition, said grooves extending outwardly from said bore, and a receptacle of resilient rubber-like material for receiving said plug and including a sealing lip at one end for contacting the margin of an aperture in said airfoil and a recess adjacent said sealing lip for seating the latter said margin, said receptacle comprising a generally frusto-conical body and a substantially cylindrical end

portion for connecting to a fluid conduit, said frusto-conical body having a bore including an inwardly extending portion in communication with and terminating at said substantially cylindrical end portion in an opening of substantially uniform diameter for registering with the bore of said plug, the wall of said inwardly extending portion being of a width less than said tubular element of said plug for elastically gripping said tubular element in separable and sealing relation.

WILLSON H. HUNTER.

CERTIFICATE OF CORRECTION.

Patent No. 2,363,592.

November 28, 1944.

WILLSON H. HUNTER.

It is hereby certified that error appears in the printed specification of the above numbered patent requiring correction as follows: Page 3, first column, line 8, for "receptacle on" read --receptacle or--; and that the said Letters Patent should be read with this correction therein that the same may conform to the record of the case in the Patent Office.

Signed and sealed this 27th day of February, A. D. 1945.
